ICE CUBER

Charles F. Belshaw and William J. La Casse, Duluth, Minn., assignors to The Coolerator Company, a corporation of Minnesota

Application August 5, 1933, Serial No. 683,732

10 Claims. (Cl. 62—112)

This invention relates to ice cubers which are adapted to be placed upon a cake of ice to form cubes therein.

The principal object of the invention is to form ice cubes in an ice cake in a relatively short time by heating a grid to melt the ice whereby the grid will sink into the ice cake to define cubes.

Another object is to completely form a predetermined number of cubes and partly form a further number of cubes in a single operation of the cuber and in a subsequent operation complete the formation of the previously partly formed cubes and completely form a further predetermined number of cubes.

5 A further object is to provide an ice cuber which will sink uniformly into an ice cake.

In the accompanying drawing illustrating a selected embodiment of the invention

Fig. 1 is a perspective view of the ice cuber.

0 Fig. 2 is a sectional view on the line 2—2 of Fig. 1 showing the ice cuber in use on a cake of ice which is partly broken away.

Fig. 3 is a detail sectional view of one corner of the tank forming part of the cuber and showing 5 the port of the tank partly in section, and

Fig. 4 is a plan view of the ice cuber showing its application on a cake of ice, the ice cuber being partly broken away.

Referring to the drawing, the ice cuber is composed of a flat metal tank 5 and a metal grid 6. At one corner of the tank is a port 7 for filling the tank with warm water and for emptying the water out of the tank. The port is soldered, welded or secured in any suitable manner to the tank and is threaded on the outer end thereof to receive a cap 8. The grid 6 is formed of one or more thin metal strips bent to shape and fastened to the bottom of the tank 5 by soldering, welding or in any other suitable manner. In the form of the invention herein shown, the grid forms a plurality of cubical recesses 9 arranged in two outside rows 10 and 11 and a central row 12. The walls of the grid are of zigzag formation comprising sections arranged at about a 5 ninety degree angle to each other. The outer side walls form recesses 9' approximately one-half of the size of the recesses 9. Small openings 13 are provided in the strips at or near the tank to permit escape of the entrapped air and 0 drainage of the water from the recesses.

Ice cubes are made by use of this invention by filling the tank 5 through the port 7 with hot water and placing the grid on the top surface of a cake of ice 14. The heat from the water will 5 be conducted from the metal tank into and

through the metal grid to the ice whereby the grid will sink into the ice cake to define cubes of ice in the cubical recesses of the grid. Where the ice cuber is placed on an uneven or tilted top surface of the ice the warm water in the 5 tank will rise to the high part of the tilted tank thereby transmitting more heat to the high part of the ice through the grid at the high part of the cuber than will be transmitted to the ice at the lower part of the cuber where the water is 10 not so warm thus tending to maintain the cuber in a level position.

In practice the ice cuber is first placed on the top surface of the cake at one side thereof and preferably at one corner thereof, and when it 15 sinks into the ice complete cubes will be formed corresponding to the recesses 9 and part cubes will be formed corresponding to the recesses 9' and these complete cubes and the outside part cubes may be easily removed from the cake by 20 using an ice pick or other suitable instrument. Then the ice cuber is positioned on the top surface of the cake in registration with the part cubes remaining on the cake and when the ice cuber sinks into the ice this time it will complete 25 the formation of those previously formed part cubes, and also form complete cubes in the recesses 9 and some additional part cubes. This operation may be repeated as often as desired. Thus, by having the grid constructed as shown 30 for example there will be seventeen complete cubes formed in the first operation of the cuber and twenty-two formed in the second and subsequent operations of the cuber and these additional cubes are formed by the zigzag shape of 35 the outside walls of the grid.

We have shown the invention in a selected embodiment which we have found satisfactory for the purpose but we are aware that changes in the form, construction and arrangement of parts 40 may be made and we reserve the right to make all such changes as fairly fall within the scope of the following claims:

We claim:

1. An ice cuber adapted to be placed on an ice 45 cake for forming ice cubes and comprising a tank for carrying a fluid heating medium, and a grid arranged beneath the tank to conduct heat from said heating medium to said ice cake.

2. An ice cuber adapted to form ice cubes on 50 an ice cake and comprising a tank for carrying a fluid heating medium, and a heat conductive grid fastened to the tank to conduct heat from said heating medium to the ice cake.

3. An ice cuber comprising a tank for carrying 55

5 a heating medium, and a grid cooperatively assembled with the tank and adapted to be arranged upon an ice cake to conduct heat from the heating medium to the ice cake, said grid having a plurality of enclosed completely formed cubical recesses and a plurality of outside part cube recesses.

10 4. An ice cuber comprising a tank for carrying a heating medium, and a grid cooperatively assembled with the tank and adapted to be arranged upon an ice cake to conduct heat from the heating medium to the ice cake, said grid being formed of zigzag metal strips arranged to provide a plurality of enclosed cubical recesses and a 15 plurality of outside part cube recesses.

15 5. An ice cuber comprising a tank for carrying a heating medium, and a grid cooperatively assembled with the tank and adapted to be arranged upon an ice cake to conduct heat from the heating medium to the ice cake, said grid comprising a plurality of zigzag walls forming a plurality of enclosed cubical recesses and a plurality of outside part cube recesses.

20 6. An ice cuber adapted to be placed on an ice cake for forming ice cubes and comprising a flat tank for carrying a heating medium, and a heat conductive grid fastened to the bottom of the tank, said grid being formed of zigzag walls and providing a plurality of enclosed cubical recesses and a plurality of outside part cube recesses.

25 7. An ice cuber adapted to be placed on an

ice cake for forming ice cubes and comprising a tank for carrying a fluid heating medium, and a heat conductive grid fastened to the underside of said tank and adapted to conduct heat from said heating medium to the ice cake, said grid having recesses therein to define the ice cubes and there being openings in the grid adjacent the bottom of the tank to permit the escape of entrapped air and water therethrough.

10 8. An ice cuber adapted to be placed on an ice cake for forming ice cubes and comprising a tank for carrying a fluid heating medium and having a flat bottom, and a heat conductive grid fastened to the bottom of the tank to conduct heat from said heating medium to the ice cake.

15 9. An ice cuber adapted to be placed on an ice cake for forming ice cubes and comprising a closed tank for carrying a fluid heating medium and having a port for filling and emptying the tank, a closure for said port, and a grid arranged beneath the tank to conduct heat from said heating medium to said ice cake.

20 10. An ice cuber adapted to be placed on an ice cake for forming ice cubes and comprising a tank for carrying a fluid heating medium, and a heat conductive grid arranged beneath the tank to conduct heat from said heating medium to said ice cake, said grid having openings below the bottom of the tank to permit the escape of air and water from the grid.
